ABSTRACT OF THE DISCLOSURE

Structural units are provided which are particularly suitable for staircases and other building structures involving a plurality of the structural units, each of which is made up of a planar tread member supporting frames on a portion of which the tread rests and wherein a supporting frame is secured at each end of the tread member. Each supporting frame has a pair of parallel spaced-apart elongate arms one of which is disposed at the front of the tread and the other of which is disposed at the rear of the tread. The supporting frame is usually a rigid rectangular closed frame, but may be of C-shape.

This invention relates to structural units more particularly for staircases, and to staircases and other building structure assembled from such units.

The problems which are solved by units embodying the present invention occur particularly in the building and design of staircases, but the units have useful application in structures other than staircases.

In the construction of most staircases nowadays, building regulations have to be observed which regulate both the length of the staircase, projected onto the horizontal, and the angle at which the staircase runs to the horizontal. In these cases the most substantial variable is the total rise of the whole stair i.e. the difference in level between the parts of the building being linked. Because of the regulation of all the other possible parameters it is not possible to mass-produce staircases for use in situations where the total rise will vary by more than a very small amount, because a fixed total length of mass-produced stringer to run between two floor levels would involve variation in angle, where total rise are different, affecting the horizontality of the treads and the relation between tread and riser, which are critical under the regulations. Alternatively, stringers of various lengths (which by definition could not be mass-produced) would involve complicated dispositions of the treads to ensure conformity with the regulations.

It is the object of the invention to provide structural units from which the staircase can be built up, which allows the assembly of the staircase from them with adjustable rise between adjacent treads so as regularly to occupy the whole of the total rise of the staircase, this being provided for in a manner which permits performance of the task by a relatively unskilled workman.

According to one aspect of the invention I provide a constructional unit particularly for staircases consisting of a tread forming member secured at each of its ends to a base end portion of a support frame, the support frames each having a pair of parallel spaced-apart arms extend-

2

ing perpendicular to the general plane of the tread, one at the front and one at the rear of the tread, and adapted when secured to an adjacent said unit to form a rigid structure. Preferably, the arms form the opposite major sides of a rigid rectangular closed frame and preferably the tread is supported within the frame to rest against the inner surface of one of the minor ends of the frame. Preferably the frame is formed from a single piece of metal bar, the free ends of the single piece being secured together at one corner of the frame. The frame may, however, be open.

According to a second aspect of the invention I provide a structure assembled from units according to the first aspect, the support frames being fixed together by the upstanding arm at the rear of a tread of one unit being fixedly secured to the upstanding arm at the front of a tread of a next unit so as to determine the rise (if any) between the treads when the structure is set up with the arms directed vertical. Preferably the support frames are secured together at two spaced-apart positions, and it is preferred that the two spaced-apart positions shall be closely adjacent to the position on each arm where the next adjacent frame parts from the arm of the frame to which it is secured. Provision may be made at the upper end of the arms for securing a handrail to them.

According to a third aspect of the invention I provide a staircase wherein vertical portions of separate structural units are secured together such as to stagger tread portions of these adjacent units apart by an amount representing the rise between the treads in the staircases.

Particular embodiments of the invention will now be described with reference to the accompanying drawings wherein:

FIGURE 1 is a perspective view of a staircase embodying the invention,

FIGURE 2 is a side view of the staircase of FIGURE 1,

FIGURE 3 is a perspective detail view,

FIGURE 4 shows the invention embodied as a bridge or gallery structure, and

FIGURE 5 shows a modified structural unit.

The staircase shown in FIGURE 1 is made up from a plurality of separate structural units 1. In the present embodiment five such units are shown to form a short staircase, but it is to be understood that within the limits of the strength of the material and the precise form of structure used, any number of these units may be secured together to form a self supporting staircase. The limits could be determined by any competent structural engineer.

Each of the units consists of two rectangular support frames 2 formed from metal bar secured one each end of a tread forming member 3. The tread forming member is suitably a plank of timber of a desired thickness, of width front to back slightly greater than the corresponding dimension of the frame so that a front portion 4 of the tread projects in front of the level frame to form a sill for the tread. In the present embodiment, the tread is secured above the bottom minor edge 5 of the frame to lie within the frame, resting on the inner surface of that base, and is secured thereby bolts passing through registering bores 6 in the tread and in the base 5. The tread and frame must be rigidly secured together so as to confer lateral rigidity of the structure which is to be made up from the units. Subject to this the tread may be secured not within the frame but could be secured below its base either to abut or to be spaced from it.

A rectangular closed frame is formed by bending metal strip round a jig to make a rectangle with one angular corner, where the free ends 7, 8 meet and are welded or otherwise firmly secured together, and three rounded corners. The radius of curvature at the round corners is small, for example half an inch. It is preferred to form the frame with the angular corner adapted to occupy the position shown in FIGURE 3, so that when secured to an adjacent unit no crevice is left for collecting dirt.

The support frame could, however, be constructed in other ways (thought to be less economical) such as welding together four straight bars to form a rectangular closed frame, or bending a single bar into C-form to make an open frame. But in each case, there must be provided a pair of parallel upstanding arms perpendicular to the plane of the tread, one at the rear of the tread and one at the front of the tread (in the embodiment shown these arms are the straight lengths 9 and 10, FIGURE 3) and means must be provided for maintaining these arms spaced rigidly apart when formed into a composite structure. In the case, for example, of a C-shaped open frame (FIGURE 5), a continuous major vertical arm 10' at one side of one unit has secured to it both of the shorter mutually inturned upper and lower vertical arms 9', 9'' of the other side of an adjacent unit, to bridge the gap between their ends. In the present case the arms are maintained spaced apart by the bottom minor edge 5 and the top minor edge 11 of the closed rectangular frame.

The staircase structure is built up by placing units side by side with a stagger between adjacent treads such that the requisite total rise is given. Then, while adjacent units are temporarily held together, bores are made through them at 12 and 13, FIGURE 3, and securing bolts passed through. Alternatively units may be welded or otherwise secured together at those positions (and also at additional points, if desired). The positions for securing together the adjacent units should be as far apart as possible along the abutting portions of adjacent support frames. The dotted lines in FIGURE 2 through the points 12, 13 respectively show how the effect of securing together the units is to set up a composite girder structure. The further apart these lines the stronger the girder for the means employed. It is preferred therefore to position the points 12, 13 as closely as possible to where bottoms or tops of adjacent frames diverge from the abutting parts on the respectively adjacent units.

The frame is also bored at the top end portion, at 14, to receive securing bolts for securing a handrail 15. It is particularly suitable to use a handrail and clamping means which is disclosed and claimed in U.K. specification No. 982,681.

It is not necessary that adjacent arms of adjacent units abut intimately together—they may be spaced apart by spacer collars such as 16, FIGURE 2, provided these are strong enough to satisfy the requirements of rigidity.

The unit uppermost in the staircase is bolted securely to the upper level of the building, at 18, FIGURE 1, and the unit lowermost in the staircase is supported against sliding movements along the ground, in the present case by bolting to a wood block 17. A metal bracket may be used, alternatively, to secure the lowermost unit to the surface on which it stands.

To assemble the staircase from a set of such units, the total rise required is accurately measured and the number of units required so that the rise per tread is within a desired limit is calculated. The rise required per tread is then accurately calculated and the units (or their frames alone) laid on a floor with the frames horizontal, and secured together. The staircase is then placed in position and secured at foot and head. The addition of a handrail confers extra rigidity. As can be seen from FIGURE 1, the frame part alone of a unit may be used

to form a handrail support conforming with the appearance of the rest of the structure.

In FIGURE 4 there is shown a structure made up of units 1 in which the treads 19 do not have forwardly or rearwardly projecting sill portions, and in which the units 1 are secured together at points 12 and 13 as before so that the treads 19 are co-planar. This way a gallery-forming or bridging structure is achieved which may bridge a gap between spaced floor portions 20. A handrail 15 may be fitted to the top of the guardrail formed by the frames 2 in the manner previously described.

Although treads of timber have been described, for use in certain applications e.g. fire escapes, metal treads would be employed.

If particularly heavy loads are to be resisted, metal bracing members may be secured between the side of the support frames. One position for such braces is shown at 21 (dot dash lines, FIGURE 2). The braces are inclined to the edges of the frame and are welded or otherwise secured to the opposed uprights.

An important quality of a stair (or any structure) formed from these units is that once erected it can, if it were not welded or otherwise permanently made up, be

- (a) easily dismantled
- (b) compactly stored
- (c) reused
  - (i) in a similar location
  - (ii) in a new location having a different total rise but requiring the same number of treads and risers as before.
  - (iii) in an extended form by the addition of extra units
  - (iv) in a reduced form by the subtraction of units
  - (v) many times

This is not to say that the structure is in any way a temporary one. But it can be used to fulfill a temporary function.

What I claim and desire to secure by Letters Patent is:

1. A structural unit having a generally planar tread, two open centered support frames having a portion on which said tread rests, one secured at each end of the tread, each support frame having a pair of parallel spaced-apart elongate arms, one said arm being at the front of the tread and one at the rear.

2. A structural unit according to claim 1 wherein the support frame is a rigid rectangular closed frame of which the lowermost portion constitutes the tread support.

3. A structural unit according to claim 2 wherein the tread is rigidly secured within the frame to one side of the rectangle.

4. A structural unit according to claim 1 wherein the frame is formed of a single piece of metal bar.

5. A rigid self-supporting structure comprising a plurality of units each constructed according to claim 1, a front said arm of one unit being secured to a rear said arm of an adjacent unit.

6. A rigid self-supporting structure comprising a plurality of separate structural units secured together, each structural unit having a floor-member and two open centered support frames rising from the floor member in spaced relation thereto laterally spaced apart along the floor forming member, a rigid joint between the support frames and the floor member, each support frame having elements at the front of the floor member and at its back secured respectively to the said means at the back and front respectively of a corresponding support frame of an adjacent said unit.

7. A structure according to claim 6 wherein the said elements of the support frames are a first single arm at the front and a second single arm parallel to the first at the back of the floor member, each single arm being secured to an adjacent unit at least at two spaced-apart positions.

8. A structure according to claim 6 wherein the said elements of the support frames are a single arm at one

side and two shorter mutually inwardly directed arms both parallel to the single arm at the other side, the two shorter arms being secured to the single arm of a said support frame of an adjacent unit at, in total, at least two spaced-apart positions along that single arm.

9. A structure according to claim 7 wherein the support frames are closed rectangular hollow frames.

10. A structure according to claim 8 wherein the support frames are each a single piece of metal bar bent generally in the shape of a C.
